UNITED STATES PATENT OFFICE.

ARTHUR P. CONANT, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE PENDANT.

Application filed June 26, 1923. Serial No. 6,580. Term of patent 14 years.

To all whom it may concern:

Be it known that I, ARTHUR P. CONANT, a citizen of the United States, residing at Fort Thomas, in the county of Campbell and State of Kentucky, have invented a new, original, and ornamental Design for Watchcase Pendants, of which the following is a specification, reference being had to the accompanying drawing, forming part thereof.

Fig. 1 is a side elevation and Fig. 2 an edge view of a watchcase pendant showing my new design its relation to the watchcase being indicated by a conventional showing of the latter by dotted lines.

I claim:

The ornamental design for a watchcase pendant, substantially as shown.

ARTHUR P. CONANT.
